UNITED STATES PATENT OFFICE.

BERNHARD C. J. ANDERSON, OF CHICAGO, ILLINOIS.

CARBURETER.

1,239,442.

Specification of Letters Patent. Patented Sept. 11, 1917.

Application filed November 4, 1915. Serial No. 59,604.

To all whom it may concern:

Be it known that I, BERNHARD C. J. ANDERSON, a citizen of the United States, residing in Chicago, in the county of Cook and 5 State of Illinois, have invented certain new and useful Improvements in Carbureters, of which the following is a specification.

Many carbureters as heretofore constructed have means for admitting what is called 10 an auxiliary supply of air, being a supply of atmospheric air admitted to the explosive mixture, after this mixture is made, for the purpose of diluting it but the objection to carbureters of this type is that the auxiliary 15 air is not thoroughly divided and mixed with the hydrocarbon to form the explosive mixture, so that all of the auxiliary air is not thoroughly carbureted and therefore a part of the fluid drawn into the cylinder is in- 20 sufficiently carbureted or in other words the hydrocarbon is not sufficiently subdivided.

One object of the present invention is to provide a carbureter in which the entire 25 volume of air passing through the carbureter will be brought into intimate contact with the liquid fuel and be thereby thoroughly carbureted, leaving the richness of the mixture largely dependent upon the velocity with which the air passes the dis- 30 charge mouth of the passage through which the liquid fuel is supplied.

Another object of the invention is to automatically proportion the capacity of the 35 throat through which the air passes the mouth of the liquid-fuel discharge passage with relation to the then existing passage through which the explosive mixture is being drawn into the cylinder.

Another object of the invention is to provide improved means for forming the discharge passage for the liquid fuel.

Another object of the invention is to provide means for supplying the discharge passage for the liquid fuel by capillary attraction, rather than by the entrainment of the liquid fuel under the influence of the suction produced by the engine.

Other objects of the invention will appear from the description which follows.

With these objects in view the invention consists in the features of novelty that are hereinafter described with reference to the

accompanying drawings which are hereby made a part of this specification, and in which:—

Figure 1 is a side elevation of the improved carbureter with the parts in normal positions, or in other words the positions which they occupy when the engine is at rest or running "on throttle."

Fig. 2 is a vertical section on the line 2—2, Fig. 1, with the parts in normal positions.

Fig. 3 is a vertical central section thereof on the line 3—3, Fig. 2, looking in the direction of the arrows, with the parts in normal positions.

Fig. 4 is a similar vertical section with the parts in the positions which they occupy when the carbureter is open to its maximum capacity.

Fig. 5 is an enlarged horizontal section on the line 5—5, Fig. 3, looking in the direction of the arrows.

Fig. 6 is an underside view of the improved carbureter with the parts in normal positions.

Fig. 7 is a similar view with the parts in the positions in which they are shown by Fig. 4.

Figs. 8, 9 and 10 are horizontal sections on the lines 8—8, 9—9 and 10—10, respectively, Fig. 3, looking in the direction of the arrows.

The body of the carbureter comprises an outer tubular wall or shell, 1, which is preferably cylindrical and of equal diameter from top to bottom, although this latter is not essential. This shell, before the parts are assembled, is entirely open at its upper end, and at its lower end it joins and rises from a web, 2, having through it openings, 3, of ample capacity for admitting the maximum volume of air required. Within the shell, 1, and concentric therewith is a cylindrical tubular wall or partition, 4, of less external diameter than the interior of the shell, 1, so as to leave between them an annular space or fuel chamber which is filled from top almost to the bottom with a wick or body, 5, of any suitable capillary substance. The bottom of this partition, or wall, joins and is preferably integral with the web, 2, and its upper end terminates

flush with the upper end of the shell, 1. The adjoining portions of the top and outer surfaces of the wall, 4, are cut away as at 6, to form a sort of annular reservoir in which a small body of free liquid fuel may accumulate. The bottom of the annular wick chamber communicates with a duct or passage, 7, which in turn communicates with a duct or passage, 8, formed through a hollow nipple, 9, which is externally screw threaded for attachment to a connection extending to a supply source of liquid fuel (not shown). The duct or passage, 7, is controlled by a valve, 10, carried by a stem, 11, threaded at, 12, for engagement with complementary threads on the interior of a tubular nipple, 13 that is rigidly carried by the shell, 1, being preferably integral with it, so that by turning the stem, 11, the valve, 10, is moved relatively to its seat which is formed around the lower end of the duct, 7, whereby the flow of liquid fuel to the annular wick chamber is controlled. To prevent leakage past the valve stem, 12, it is surrounded by a stuffing box, 14, the cap of which is screwed onto the lower end of the nipple, 13.

Originally the valve, 10, is set a slight distance from its seat—just far enough away to permit the passage of just the quantity of liquid that is necessary for running “on throttle”—and this original setting of the valve is accomplished by turning the valve stem, 11, manually, but thereafter, in order to meet the requirements for greater speeds the valve is moved automatically by connections hereinafter described between the valve stem and the throttle lever.

At its top the wall, 4, has an inwardly extending flange which is undercut, so as to reduce it to a knife-edge annular lip, 15.

The shell, 1, is surmounted by a spacing ring, 16, which is held down by a clamping member, which in the form of the invention shown in the drawings consists of a ring 17, having at its outer edge a downwardly presented annular flange, 18, which snugly embraces a radial flange, 19, with which the upper portion of the shell, 1, is provided, and an upwardly presented annular flange, 20, which snugly embraces a radial flange, 21, on the bottom of the cap or dome, 22, of the carbureter. The annular flanges, 18 and 20, are for the sole purpose of centering the parts and thereby facilitating the work of assembling them. For holding the spacing ring in place when the dome or cap 22, is removed for any purpose the clamping ring, 17, may be secured to the shell, 1, by one or more screws, 23, the heads of which are countersunk so as to be flush with the top surface of the clamping ring. For permanently securing the clamping ring in place, and holding the dome or cap of the carbureter in place, a number of screws, 24,

are passed through the flange, 21, clamping ring, 17 and spacing ring, 16, and screwed into the flange, 19.

The holding of the spacing ring in place when the cap or dome is removed, is the only object in using a separate clamping ring interposed between the spacing ring and the cap or dome. Otherwise the bottom of the flange, 21, might contact directly with the spacing ring and the separate clamping ring might be dispensed with altogether.

The inner edge of the clamping ring is chamfered or cut away on its top side so as to reduce it to a knife-edge lip, 25, which is of the same diameter as the knife-edge lip, 15, already described and these lips are separated by a space equal to the thickness of the spacing ring, 16, which is very thin. For a one-inch carbureter for instance it is only about one one thousandth of an inch and preferably is made from a sheet of thin paper, which being frail makes the use of the separate clamping ring desirable. This manner of forming the discharge passage for the liquid fuel is far superior to forming it by a milling or machining process which is intended to provide two flat surfaces, one of which is in a plane only a small fraction of an inch away from the plane of the other. By this latter process accuracy for even one measurement is next to impossible and variation or adjustment for different measurements is wholly impossible without further milling. But by the use of a spacing ring or rings, between flat milled surfaces, all adjustments are made possible.

As thus far described the operation of the device is as follows.

The fuel supply device (which is not shown because devices for this purpose of many different constructions are well known to those skilled in the art) will maintain free liquid fuel in the annular wick chamber at a certain level. The wick, 5, dipping into this liquid will, by capillary attraction, carry it up to the thin annular discharge passage, 26, in which it is spread out in a very thin film and as the suction produced by the engine draws in air and causes it to flow past the knife-edge lips, in the manner hereinafter described, the liquid fuel will be thoroughly vaporized and the air thoroughly carbureted and drawn into the interior of the dome or cap, which constitutes or has a mixing chamber, 27, from which it passes through the outlet port, 28, and thence on to the engine cylinder.

The outlet, 28, is cylindrical and is controlled by a disk valve, 29, which, for the sake of distinction will hereinafter be called the “choke-valve,” although it has the function of a “throttle valve.” This choke-valve is approximately of the same diameter as the outlet port which it occupies, so as to be easily slidable into and out of it with

a piston fit. This choke-valve is carried by a tubular stem, 30, which has near its lower end perforations located diametrically opposite each other, into which perforations extend the unthreaded ends of screws, 31, which screws occupy correspondingly threaded perforations formed through the opposite sides of a sleeve, 32, hereinafter called the "camsleeve." These screws 5 connect the tubular valve stem, 30, and the cam sleeve, 32, so that they are incapable of any movement independently of each other. The cam sleeve surrounds loosely so as to be capable of turning freely thereon a tube, 10 33, hereinafter called the "stop tube," which projects downward from the web, 2. The interior of the cam-sleeve is of two diameters, resulting in an internal shoulder, 34, near its lower end, which is adapted under 15 some conditions to contact with the lower end of the stop-tube, thereby forming a stop for limiting the upward movement of the cam-sleeve, 32, and consequently of the tubular valve stem, 30, and the choke-valve, 20 25 29, which it carries.

The interior of the tubular valve-stem, 30, has near its lower end internal screw threads for engagement with a correspondingly threaded portion, 35, of a stem, 36, 30 which passes completely through the tubular valve-stem, 30, and projects therefrom at both its upper and lower ends. The projecting lower end of the stem, 36, is adapted to be grasped or to receive an implement for 35 turning it and thereby adjusting it lengthwise relatively to the tubular valve-stem, 30, for the purpose of regulating the tension of a coil spring, 37, which surrounds the upper projecting end of the stem, 36, and 40 exerts its pressure in one direction against said stem, through the medium of a collar, 38, carried by it and in the other direction against a valve, 39, with a tendency to hold it closed or seated. This valve, 39, normally 45 bears upon the top of the choke-valve, 29, and closes one or more ports or passages, 40, formed through it.

In order to prevent the stem, 36, from turning at random under the influence of 50 vibration, the stem, 36, is made of square or other non-circular shape as at, 41, and a spring clamp, 42, is seated in openings, 43, formed in opposite sides of the tubular valve-stem, 30. This clamp has delicate spring 55 arms which engage the noncircular portion, 41, of the stem, 36, with sufficient force to prevent it from turning at random but not with sufficient force to prevent it from being turned easily for the purpose of adjusting 60 the tension of the spring, 37.

46 is a valve which may approximately be called the throttle or "throttle valve." Its purpose is to control and regulate the volume and velocity of the current of 65 air flowing past the lips, 15 and 25, of the

mouth of the thin annular fuel-discharge passage, 26, and it is so shaped that the capacity of the annular passage or throat through which the air flows past the mouth of the annular fuel-discharge passage will 70 depend upon the position of the throttle itself. Its exterior is of tapering—preferably conical—shape and the angle of its taper corresponds approximately with the angle or taper of the downwardly flaring internal surface, 45, of the mixing chamber, 27, with which the choke-valve, 29, cooperates, the surfaces of the mixing chamber and the throttle being at all times approximately parallel. 75

When the carbureter is working "on throttle" and the choke-valve closed the total capacity of the passage for the flow of the explosive mixture to the engine will be represented by the capacity of the port 80 or ports, 40, through the choke-valve, 29, but when the outer-port, 28, is more or less opened by moving the choke-valve away from it, in the manner hereinafter described, the capacity of the passage for the 85

explosive mixture to the engine will be represented by the capacity of the annular space, or passage or throat between the periphery of the choke-valve and the flaring inner surface, 45, of the mixing chamber, 95 plus the capacity of the port or ports, 40, to the extent that these latter are uncovered by the lifting of the valve, 39, under the influence of the suction of the engine. The farther the choke-valve is moved away from 100

the port, 28, the greater will be the capacity of this annular passage or throat around it. By means hereinafter described the choke valve and throttle, 46, are indirectly connected so that while they may, when desired, be adjusted relatively to each other, still normally they are compelled to move together during the normal operation of the carbureter, so that as the choke valve is 105 moved away from the port, 28, and the annular passage around it thereby increased, the throttle will be moved away from the discharge mouth of the thin annular fuel-discharge passage, 26, between the annular lips, 15 and 25, thereby increasing the one at 110

a ratio corresponding with the increase of the other.

The throttle, 46, is secured to the upper end of a tubular stem, 47, which passes down through a tubular guide-post, 48, rising from the web, 2, and also through the web, 2, and through the stop tube, 33, whereby it is guided and held against lateral movement. The throttle is normally held 115 yieldingly in elevated position by a coil spring, 49, which surrounds the guide post, 48, and bears upward against the under side of the throttle and downward against the web, 2.

The lower end of the tubular valve stem, 120

125

47, is externally screw threaded as at 50, and onto this threaded portion is turned an adjusting nut, 51, the top side of which bears against the lower end of the cam-sleeve, 32, whereby the upward movement of the valve-stem, 47, and consequently the throttle, 46, under the influence of the spring, 49, is ultimately limited. By turning this nut, 51, the position of the throttle 10 with relation to the lip, 15, and the position of the choke valve with relation to the port, 28, may be adjusted, but the adjustment should be such that the throttle never contacts with the lip, 15. The purpose of this 15 adjustment is to regulate the capacity of the annular throats around the throttle and choke valve, under any given position of the throttle lever. The cam sleeve, 32, has a slot, 52, which occupies an approximately 20 helical course and into this slot projects a rigid pin, 53, projecting radially from the fixed stop tube, 33, so that when the cam sleeve is turned in the direction of the arrow placed upon it in Figs. 1 and 2, the pin 25 53 will cause the cam-sleeve to move downward and the lower end of this sleeve being in contact with the nut, 51, the latter will be forced downward thereby drawing the valve-stem, 47, downward and in turn moving 30 the throttle and choke valve downward increasing the throats around them. A stop pin, 54, carried by the cam sleeve projects into the cam slot, 52, in position to engage the fixed pin, 53, and limit the movement of 35 the cam-sleeve in the direction of the arrow in Figs. 1 and 2, but of course the same result could be attained by terminating the slot, 52, in the position of the pin, 54.

By making the cam of the cam sleeve in 40 the form of a slot the edge of that portion, 55, of the metal of the sleeve which forms the top wall of the slot will coöperate with the fixed pin, 53, and prevent any strictly endwise movement of the cam sleeve. This 45 has the advantage of preventing back firing from forcing the choke-valve and throttle downward and consequently in some positions of the parts lessening the liability to the ignition and explosion of the contents 50 of the carbureter.

The cam sleeve, 32, carries a radially projecting arm, 56, that is secured to it by means of a split ring, 57, formed integrally with it and provided with a perforation, 58, 55 or other feature by which it is jointed to a connection with the throttle lever (not shown).

This construction is such that by moving 60 the throttle arm, 56, forward in the direction of the arrow, α , in Fig. 6, the tubular stem, 47, and with it the stem, 30, is drawn downward in opposition to the force of the spring, 49, thereby increasing the capacity of the annular throat around the throttle 65 for the flow of air past the mouth of the

annular discharge passage, 26, and also the throat around the choke valve, 29, and by moving said throttle arm in the opposite direction or backward as indicated by the arrow, γ , the spring, 49, will move the stem, 70 47, and throttle, 46, upward, as indicated by dotted lines in Fig. 3, as far as permitted by the pin, 53, depending upon the angular position of the cam sleeve, 32, or ultimately by the contact of the shoulder, 34, of the cam sleeve with the lower end of the stop tube, 33. 75

Let this be carefully noted, that when the choke valve, 29, and the throttle, 46, are approximately closed, or near their respective 80 coöperating parts, (which parts can not appropriately be called "seats" for the valves as neither of these valves comes in direct contact with its coöperating part) if the stems, 30 and 47, be moved downward the 85 throats or passages aforesaid are enlarged because while being of the same cross sectional area, they, nevertheless, differ in diameter and therefore in capacity or total cross sectional area, the throat between the 90 throttle and the discharge mouth of the annular fuel discharge passage, 26, being greater (preferably say two to one) than the throat between the choke valve and the coöperating part of the outlet port, 28, of 95 the carbureter.

The engine, by its suction is bound to draw in its complement of fluid, although this fluid will be more or less rarefied, depending upon the resistance to the flow of 100 the entering fluid and the freedom (or conversely the resistance) to the inflow of the fluid will depend upon the capacity of the inlet passages which in turn depend upon the capacity of the inlet passages which in 105 turn depend upon the positions of the several valves.

In the regular operation of the engine these valves are manipulated for the purpose of changing the capacity of the fluid 110 passages, (or in other words for different speeds) and this manipulation will now be described, but these movements of the valves should not be confounded or confused with their adjustments for meeting special conditions. 115

The operation of the device is as follows:

Whatever may be the liquid fuel admitted 120 through the duct or passage, 8, in starting the engine a richer mixture is required than when the engine has attained a running speed. To this end it is desirable to admit through the duct, 7, an increased quantity 125 of liquid fuel when the engine is to be started. To this end the valve stem, 11, is provided with an arm, 59, that projects from it at such an angle that when the throttle lever is in normal position, the valve, 10, will be held a slight distance from its seat, so as to admit to the annular wick cham- 130

ber a normal supply of fuel. When the engine is to be started the throttle lever is moved in one direction, which for the sake of distinction may be called backward as indicated by the arrow *y* in Fig. 6 and as a result of this backward movement of the throttle lever, the valve stem, 11, will be turned a short distance in one direction so as to increase the space between the valve, 10, and its seat and thereby admit an increased volume of fluid to the annular wick chamber. This same backward movement of the throttle lever will move the choke valve, 29, and the throttle, 46, from the positions shown by full lines in Fig. 3, to the positions shown by dotted lines in the same figure, or rather permits the spring, 49, to do so. This movement of the throttle, 46, will reduce the capacity of the throat around it so that the air will pass through this throat at a greater velocity than when the throttle is in a lower position. The effect of this increase in the velocity of the air is to increase the suction at the mouth of the annular discharge passage, 26, and thereby draw from said annular passage a greater quantity of liquid fuel. This same operation will move the choke valve farther into the outlet port, 28, and there maintain it so as to practically close the outlet port so far as any space around the choke valve is concerned, so that thereafter the only fluid drawn in by the suction of the engine will be that which is drawn in through the port, or ports, 40, and this in turn will depend upon the lifting of the valve, 39, under the influence of the suction. In order to still further facilitate the starting of the engine, assuming that the liquid fuel supplied through the duct, 7, is of low volatility, I provide means under the control of the operator for admitting to the annular passage, 26, a supply of liquid fuel of higher volatility. This may consist of a tube, or pipe, 60, which leads from a source of liquid fuel, say gasoline, and has a valve, 61, located within convenient reach of the operator so that at the instant of starting it may be opened to admit a supply of gasoline, or other fuel of high volatility to the annular passage, 26. The duct through which this liquid fuel passes is controlled by a manually adjustable needle valve, 62, which is intended to be set so that it will regulate and control the supply of fuel when the valve, 61, is open. The engine having been started, the throttle lever is moved in the direction opposite that last above described, *i. e.*, forward and this, through the medium of a link, 63, jointed at one end to the arm, 59, and at the other end to an arm, 64, projecting from the ring, 57, moves the valve, 10, away from its seat and at the same time opens the choke valve, 29, and throttle, 46,

so as to increase the capacity of the annular throats, or passages around them. It will be observed that the link connections between the ring, 57, and the lever arm, 59, are "universal", that is to say they have perpendicularly arranged joints, which permit the ring, 57, to rise and fall relatively to the arm, 59, and at the same time permit the ring, 57, and arm, 59, to move in circular paths concentric with the parts to which they are respectively secured. 70

It has heretofore been intimated that the nut, 51, is for the purpose of adjusting the position of the throttle, 46, relatively to the mouth of the annular fuel discharge passage, 26. This nut, 51, which is of non-circular shape is engaged by a sector arm, 65, having a slot, 66, which is concentric with the nut, 51, and through which passes a binding screw, 67, tapped into the lever, 85 56, for securing the sector arm in any position relatively to the arm, 56, to which it may be adjusted. In order to fully explain the purpose of this sector arm, let it be supposed that with the throttle arm, 56, in any given position, the space or throat around the throttle, 46, is greater or less than desired. If so, by loosening the binding screw, 67, and turning the sector arm, 65, the nut, 51, will be turned and in turn will move 90 endwise the hollow stem, 47, carrying the throttle and thus adjust the position of the throttle relatively to the mouth of the annular passage, 26. 95

The above described backward movement 100 of the cam sleeve, 32, under the influence of the throttle lever is limited by the contact of the inner end of the slot, 52, with the fixed pin, 53, but as soon as this backward movement commences a shoulder, 68, on the 105 sleeve comes in contact with a pin, 69, carried by a ring, 70, that surrounds, so as to be capable of turning thereon, the stop tube, 33. This ring is held in normal position by coil springs, 71, each of which is connected 110 at one end to a pin, 72, projecting radially from the ring, 70, and at the other end to a pin, 73, projecting radially from a ring, 74, that is non-rotatively secured to the stop tube, 33, as by a screw, 75. 115

It will be observed that a carburetor constructed as above described does not admit an auxiliary supply of air to the explosive mixture after it is formed, but on the contrary all air passing through the carburetor 120 is brought into intimate contact with the thin film of liquid fuel that is discharged or exhausted from the mouth of the thin annular fuel passage, 26, and in consequence of this latter the entire volume of air is thoroughly carbureted. 125

What I claim as new is:

1. A carburetor having a fuel-discharge passage formed by two parts having opposing surfaces, a spacing ring interposed between 130

said opposing surfaces and leaving between them a film-like passage for the liquid fuel, terminating in an annular mouth having knife-edge lips, a throttle of tapering or graduated shape arranged opposite said mouth in close proximity to said lips and with its smaller end presented in the direction of the flow, and means for adjusting said throttle relatively to said mouth.

10. A carbureter having in combination a shell or casing having concentric walls spaced apart to leave between them an annular fuel chamber, a clamping member surmounting said walls, a spacing ring interposed between the clamping member and the top of the outer wall whereby a film-like discharge passage is left between the clamping member and the top of the inner wall, means for securing the parts together in operative relation to each other and a wick disposed in said annular fuel chamber.

15. A carbureter having in combination a shell or casing having within it an annular liquid-fuel chamber and an annular film-like fuel discharge passage, having an annular discharge mouth having knife-edge lips, a body of capillary material occupying said chamber and extending to said annular passage, means for supplying liquid fuel to said chamber, and means for regulating the flow of air past the mouth of the discharge passage.

20. A carbureter having in combination a shell or casing having within it an annular liquid-fuel chamber and an annular film-like fuel-discharge passage having an annular discharge mouth having knife-edge lips, a body of capillary material occupying said chamber, means for supplying liquid fuel to the bottom of said fuel chamber, and means for causing and regulating the flow of air past the mouth of the discharge passage, a part of the apparatus being shaped to form an annular auxiliary fuel reservoir communicating with said annular discharge passage.

25. A carbureter having in combination a shell or casing having concentric walls spaced apart to leave between them an annular fuel chamber, a body of capillary material occupying said chamber, a clamping member, a spacing ring interposed between the clamping member and the top of the outer wall whereby a film-like discharge passage is left between the clamping member and the top of the inner wall and means for securing the parts together in operative relation to each other.

30. A carbureter having in combination a shell or casing having concentric walls spaced apart to leave between them an annular fuel chamber, a body of capillary material occupying said chamber, a clamping member, a spacing ring interposed between the clamping member and the top of the outer wall whereby a film-like discharge passage is left between the clamping member and the top of the inner wall and means for adjusting said throttle relatively to said mouth.

35. A carbureter having in combination a shell or casing having concentric walls spaced apart to leave between them an annular fuel chamber, a clamping member surmounting said walls, a spacing ring interposed between the clamping member and the top of the outer wall whereby a film-like discharge passage is left between the clamping member and the top of the inner wall and adjacent portions of the inner edges of the inner wall and clamping member being reduced to knife-edge lips which form the mouth of said discharge passage.

40. A carbureter having in combination a shell or casing having concentric walls spaced apart to leave between them an annular fuel chamber, a clamping member surmounting said walls, a spacing ring interposed between the clamping member and the top of the outer wall whereby a film-like discharge passage is left between the clamping member and the top of the inner wall, the inner wall having at top an inwardly presented annular flange and the adjacent edges of said flanges and clamping member being reduced to knife-edge lips which form the mouth of said passage, and means for securing the parts together in operative relation to each other.

45. A carbureter having in combination a shell or casing having concentric walls spaced apart to leave between them an annular fuel chamber, a clamping member in the form of a ring surmounting said walls, a spacing ring interposed between the clamping ring and the top of the outer wall whereby a film-like discharge passage is left between the clamping ring and the top of the inner wall, the inner wall having at top an inwardly presented annular flange and the adjacent edges of said flanges and clamping member being reduced to knife-edge lips which form the mouth of said passage, and means for securing the parts together in operative relation to each other.

50. A carbureter having in combination a shell or casing having concentric walls spaced apart to leave between them an annular fuel chamber, a body of capillary material occupying said chamber, a clamping member, a spacing ring interposed between the clamping member and the top of the outer wall whereby a film-like discharge passage is left between the clamping member and the top of the inner wall, means for securing the clamping ring to the shell and clamping the spacing ring between them, a hollow dome surmounting the clamping ring and having an outlet port and means for securing together in operative relations to each other the shell, the spacing ring, the clamping ring and the hollow dome.

55. A carbureter, having, in combination, a shell or casing having a liquid-fuel chamber, a duct communicating therewith for supplying it with liquid fuel, a valve for controlling said duct, said shell or casing having a film-like annular discharge passage communicating with said fuel chamber and having an annular discharge mouth having knife-edge lips, a tapering throttle arranged in operative relation to said annular discharge mouth, means connecting said throttle to the valve, and a clamping member surmounting the shell or casing and the duct, the clamping member being interposed between the shell or casing and the duct, the clamping member being adapted to hold the shell or casing and the duct in operative relation to each other.

- tle and the valve aforesaid, and means for operating said connecting means whereby said valve and throttle are operated simultaneously.
- 5 11. A carbureter having in combination a shell or casing having a film-like annular liquid fuel discharge passage having an annular discharge mouth, said shell having also a hollow dome providing a mixing 10 chamber, the inner wall or surface of which flares, a throttle arranged opposite said annular discharge mouth, said throttle being tapered on its exterior substantially parallel with the inner surface of the mixing chamber, a choke valve arranged in operative relation to and adapted to control said outlet port and means for simultaneously operating said choke valve, the throttle and annular mouth being of greater diameter than 15 the outlet port.
12. A carbureter having in combination a shell or casing having a liquid-fuel chamber, having an annular discharge passage terminating in an annular mouth, said casing having also an outlet port adapted for communication with the engine cylinder, a choke valve arranged in operative relation to and adapted to control said outlet port, a throttle arranged opposite said annular mouth, 20 concentric stems carrying said choke valve and throttle, respectively, and means for simultaneously moving said stems lengthwise for simultaneously operating said throttle and choke valve.
- 25 13. A carbureter having in combination a shell or casing having a liquid fuel chamber having an annular discharge mouth, said shell or casing having also an outlet port adapted for communication with the engine, 30 a choke valve arranged in operative relation to said outlet port, said choke valve having through it a port or opening for the passage of the explosive mixture, a tubular stem carrying said choke valve, a spring seated valve arranged against the inner side of the 45 choke valve and adapted to control said port or opening, a stem passing centrally through both of the valves aforesaid and through the tubular stem of the choke valve, a spring surrounding said central stem for holding 50 the spring seated valve aforesaid to its seat, said central stem having threaded engagement with the tubular stem of the choke valve for adjusting the tension of said spring, and yielding means interposed between the central stem and the tubular stem 55 for preventing said central stem from turning at random.
14. A carbureter having in combination a shell or casing having a liquid fuel chamber 60 having an annular discharge passage terminating in an annular mouth, said casing having also an outlet port adapted for communication with the engine cylinder, a choke valve arranged in operative relation to and 65 adapted to control said outlet port, a throttle arranged in operative relation to said annular mouth, concentric tubular stems carrying the choke valve and throttle, respectively, the tubular stem of the throttle having 70 its lower end screw threaded, a nut turned onto said screw thread, a cam sleeve engaging said nut, means connecting the cam sleeve and the stem of the choke valve, said cam sleeve having a helically disposed cam 75 surface, a fixed stop pin operatively related to said cam surface whereby when the cam sleeve is rotated in one direction, it is moved endwise to correspondingly move the tubular stems of the choke valve, the throttle, and a 80 spring normally tending to move the choke valve and throttle in the opposite direction.
